QUILTING FRAME

William E. Myers, 111 E. Broadway,
Cushing, Okla. 74623

Filed Oct. 29, 1974, Ser. No. 518,532

Term of patent 14 years

Int. Cl. D15—06

U.S. Cl. D15—66

FIG. 1 is a front elevational view of a quilting frame showing my new design, the rear elevational view being the same.

FIG. 2 is a top view thereof.

FIG. 3 is an elevational view of one side thereof.

FIG. 4 is an elevational view of the other side thereof.

FIG. 5 is a bottom view thereof.

I claim:

The ornamental design for a quilting frame, as shown.
